Primary Examiner — Andrew Kerr*Assistant Examiner* — Courtney J Clark-Rasheed(74) *Attorney, Agent, or Firm* — Hanley, Flight & Zimmerman(57) **CLAIM**

The ornamental design for a “grill”, as shown and described.

DESCRIPTION

FIG. 1 is a front perspective view of a grill.

FIG. 2 is a front view of the grill of FIG. 1.

FIG. 3 is a rear view of the grill of FIG. 1.

FIG. 4 is a right side view of the grill of FIG. 1.

FIG. 5 is a left side view of the grill of FIG. 1.

FIG. 6 is a top view of the grill of FIG. 1; and,
FIG. 7 is a bottom view of the grill of FIG. 1.

The broken lines in the drawings depict portions of the “grill” that form no part of the claimed design.

1 Claim, 7 Drawing Sheets(56)
